Primary Examiner — Carla Jobe Wright(74) *Attorney, Agent, or Firm* — Cantor Colburn LLP(57) **CLAIM**

The ornamental design for a cover for electronic communications device, as shown and described.

DESCRIPTION

FIG. 1 is a front perspective view of a cover for electronic communications device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The dot-dash broken line in FIG. 3 represents a boundary of the claimed design. The dash-dot broken lines illustrate environmental portions of the cover for electronic communications device that form no part of the claimed design.
